(No Model.)

E. A. FRANKLIN.
CARTRIDGE CRIMPER.

No. 417,673.

Patented Dec. 17, 1889.

UNITED STATES PATENT OFFICE.

EDWARD A. FRANKLIN, OF BRENHAM, TEXAS, ASSIGNOR TO BAILEY,
FARRELL & COMPANY, OF PITTSBURG, PENNSYLVANIA.

CARTRIDGE-CRIMPER.

SPECIFICATION forming part of Letters Patent No. 417,673, dated December 17, 1889.

Application filed July 5, 1888. Renewed September 24, 1889. Serial No. 324,885. (No model.)

To all whom it may concern:

Be it known that I, EDWARD A. FRANKLIN, of Brenham, in the county of Washington and State of Texas, have invented a new and useful Improvement in Cartridge-Crimpers; and I do hereby declare the following to be a full, clear, and exact description thereof, reference being had to the accompanying drawings, forming part of this specification, in which—

10 Figure 1 is a plan view of my improved cartridge-crimper. Fig. 2 is a longitudinal sectional view on the line $x-x$ of Fig. 1. Fig. 3 is a horizontal longitudinal section on the line $y-y$ of Fig. 2. Fig. 4 is an end view. Fig. 15 5 is an end view of a modified form. Fig. 6 is a similar view showing a modified form of the indenting-head of the tweezer-jaws. Fig. 7 is a partial longitudinal section on the line $z-z$ of Figs. 5 and 6, showing the operation of 20 crimping a cartridge.

Like letters of reference indicate like parts in each.

My invention relates to improved devices for crimping cartridge-shells, so as to retain 25 the load within the same.

In the drawings, $a-b$ represent the arms of the crimping-tweezers, which are pivoted at the point c and are provided with a spring d . The jaws of these tweezers at their outer ends 30 are provided with projecting heads e , having inclined biting-faces extending in opposite directions. Situate between the jaws of the tweezers is the shell-holder h , having a slightly flaring mouth and openings in the sides opposite the biting-heads of the tweezer-jaws. This shell-holder is pivoted to the body of the tweezers, and is provided with a central core i , of less diameter than the interior of the shell-holder, so that when the shell is 35 placed within the holder the core shall fit within the interior of the shell. Situated centrally within the head of the core i is a spring printing-stamp k , the purpose of which is to stamp or letter the outer wad of the cartridge.

Secured to one side of the shell-holder h is a 45 spring-knife m , adjustably fitted in a slot in the holder by means of a set-screw n . The point of this knife is situated directly opposite an opening in the shell-holder at or about the top of the central core. The purpose of 50 this knife is to cut off the end of the shell above the crimping-point.

The operation of my improved device is as follows: A cartridge having been loaded is placed mouth downward in the shell-holder, 55 the core i fitting within the shell. By closing the arms and jaws of the tweezers the biting-heads e indent the shell directly above the upper wad. By then turning the shell the indenture made is extended so as to form 60 a crease of the desired length. At the same time the printing-stamp forms the desired character or letter on the face of the upper wad.

I am aware that cartridges have been 65 crimped by indenting and creasing the same above the wad, and I do not desire to claim the same, broadly; but,

Having thus described my invention, what I claim, and desire to secure by Letters Patent, is—

1. In a tool for crimping cartridges, the combination of tweezers having indenting-jaws, a central core, and an adjustable knife for cutting the end of the shell, substantially as 75 70 described.

2. As an improved article of manufacture, a cartridge-crimper comprising tweezers having biting-heads, an interposed core and printing-stamp arranged within said core, a shell-holder surrounding the core, and a trimming-knife, substantially as described.

In testimony whereof I have hereunto set my hand this 9th day of June, A. D. 1888.

EDWARD A. FRANKLIN.
